CURRENT DISTRIBUTING MEANS FOR
ELECTROLYTIC PROCESSES

Robert C. Olsen, Detroit, Mich., assignor to
Ternstedt Manufacturing Company, Detroit,
Mich., a corporation of Michigan

Application December 24, 1940, Serial No. 371,486

1 Claim. (Cl. 204—228)

Considerable difficulty is encountered in electrolytic processes in obtaining the desired distribution of current over the surfaces of the electrodes. This is particularly true in processes which require relatively narrow limits of the current densities at the electrode surfaces in order to effect the desired results. In chromium plating, for example, or in bright nickel plating, fairly accurate control of current densities is necessary to maintain satisfactory brightness of the deposits. The extent of electrolytic action at the surfaces, as, for example, the quantity or thickness of electrodeposits, is also dependent upon the current density over the areas involved and uniformity of actions is obtainable only by accurate control of current distribution.

It is recognized that the difficulty in question is due to varying resistances offered to the flow of current between the electrodes caused usually by irregular contour of the electrodes and the resulting variations in the length of the path of current flow. In efforts to improve the operation, it is common practice in the electroplating art, for example, to modify the form of the anode to make it conform more closely to the contour of the cathode or "work." Cathodic appendages, commonly termed "robbers," are also frequently employed to shield portions of the cathode that are nearer the anode. The latter devices are of only limited utility since they merely divert current from the shielded areas. Shaped anodes are very generally used but are not feasible in operations where the one electrode, usually the anode, is fixed and the other electrode travels through the electrolyte.

As distinguished from the above described expedients, the present invention is concerned with a current intercepting and redistributing means entirely unconnected electrically except through the electrolyte with either of the electrodes. This means may however, as a matter of convenience, particularly where one electrode, as the cathode or work, travels through the electrolyte, be supported upon the electrode by suitable insulating means. Its mechanical features may be widely varied but comprise essentially a current collecting part positioned in the electrolyte in the path of current flow and a current distributing part, said parts so proportioned and positioned with reference to the anode and cathode as to collect, direct, and/or redistribute the current in accordance with the desired apportioning of current densities. The material of the device will vary, of course, with the nature of the electrolyte and the process. It should ordinarily be inert in the

electrolyte but may include, particularly in the current discharging or redistributing portion, materials adapted to supply coatings for the cathode or work. In electroplating operations, for example, the current distributing part may be of the metal being deposited such as nickel, or, where the metal being deposited is supplied by the electrolyte, as in the usual chromic acid chromium plating baths, such part may be of any suitably inert metal, as lead, lead-coated copper, or soft steel.

It will be understood that, if plating metal is being supplied in part by the current distributing means, such metal must be replenished at intervals. It is therefore convenient, in such cases, to provide means for removal or replacing of the current distributing portion. The current collecting portion, however, is of indefinite life since electrolytic action at its surface tends to deposit metal rather than remove it.

In the accompanying drawing

Figure 1 is a diagrammatic view illustrating the application of the invention.

Figure 2 is a view more in detail, showing the form of the current distribution modifying device as designed for a particular use.

Figure 3 is a cross section on line 3—3 of Figure 1.

In the drawing, 5 indicates a suitable receptacle, hereinafter referred to as a tank, shown in cross-section and which may be of any size and length depending upon the character and extent of the electrolytic process.

The electrolyte is marked 7. Over the tank are positive and negative bus bars 9 and 11 and current is supplied by a generator G. The anode 13 is supported as at 15 on the positive bus bar and the cathode 17—the work—is supported on the negative bus bar by means such as a hook 19. In the embodiment shown the work is a part of a motor vehicle grille. It is irregular in shape and as explained above the work would receive a coating of unequal thickness were no provision made to correct such a defect.

The difficulty is overcome by the use of a redistributing means in the form of an intermediate anode marked 21 shaped to conform to the outline of the work as shown by Figure 1. In practice the work travels through the electrolyte and it is desirable to support the anode 21 from the work itself so that it moves with the work and the space relation between the intermediate anode and the work remains unchanged. The anode 21 may be of nickel wire in the process of plating a surface with nickel.

In order to gather more current there is associated with the intermediate anode a collector plate marked 23. The ends of the nickel wire 21 are secured to the collector plate as shown at 25. To support the assembly of parts 21 and 23 there are used insulating members of Bakelite marked 27 and 29. Member 27 carries a hook 31 which engages in an opening in the lower end of the work. Member 29 carries an undercut attaching element 33 for engaging an upper part of the work as shown by Figure 3.

By the use of the auxiliary current intercepting and redistributing means the thickness of the coating may be made substantially uniform over the whole surface of the work. The result is accomplished by the very simple expedient shown and is well adapted for use in a process where the work travels through the electrolyte.

While the invention has been described herein as applied specifically to the electroplating art for which it was more particularly designed, it will be understood that, in its broader aspect, it is applicable to other fields in which it becomes desirable to modify the distribution of electric

current over the surfaces of electrodes employed in electrolytic processes.

I claim:

The combination with a tank, an electroplating electrolyte therein, anodes fixedly supported in said electrolyte, work-supporting means arranged to travel through said electrolyte past said anodes and to support irregularly shaped work, and means to cause electric current to flow through said electrolyte between said anodes and said work, of a current-collecting and distributing device spaced from said anodes and unconnected therewith but positioned in the path of said current, said device having a current-collecting part composed of metal other than the plating metal positioned nearer the anodes than the work and a current-distributing part composed of plating metal positioned nearer the work and conforming in contour to the contour of irregularities of the work throughout substantially the entire area of the irregularities, and means for insulatingly supporting said device fixedly upon the work so as to travel therewith.

ROBERT C. OLSEN.
